UNITED STATES PATENT OFFICE

141,712

DESIGN FOR A PINTLE CHAIN

Clarence K. Johnson, Portland, Oreg., assignor
to Electric Steel Foundry, Portland, Oreg., a
corporation of Oregon

Application March 21, 1945, Serial No. 118,604

Term of patent 14 years

(Cl. D54—3)

To all whom it may concern:

Be it known that I, Clarence K. Johnson, a citizen of the United States, residing at Portland, in the county of Multnomah and State of Oregon, have invented a new, original, and ornamental design for a Pintle Chain, of which the following is a specification, reference being had to the accompanying drawing, forming part thereof.

Fig. 1 is an elevational view of one side of three connected links of a pintle chain embodying my new design;

Fig. 2 is a top plan view of the chain shown in Fig. 1;

Fig. 3 is an elevational view of the side of the chain opposite that shown in Fig. 1; and

Fig. 4 is a sectional view of a leg of one of the links of the chain with the section taken substantially on a line 4—4 of Fig. 2 and viewed as indicated by the arrows.

I claim:

The ornamental design for a pintle chain, substantially as shown.

CLARENCE K. JOHNSON.
